UNITED STATES PATENT OFFICE.

JOHN A. RICE, OF CLEVELAND, OHIO, ASSIGNOR, BY DIRECT AND MESNE ASSIGNMENTS, OF TWO-FIFTHS TO JOSEPH F. RICE, TWO-FIFTHS TO MAX B. SOLOMON, AND ONE-FIFTH TO JOHN H. GESING, ALL OF CLEVELAND, OHIO.

CLOSURE FASTENER.

Application filed April 18, 1925. Serial No. 24,211.

My invention is an improvement in closure fasteners, and more particularly adapted for use in connection with garage doors and the like.

5 An important object of my invention is to provide a closure fastener which may be used on either right or left swing closures and which may be quickly and easily installed thereon.

10 Another object of my invention is to provide a device of the above named character which is extremely inexpensive to manufacture and which is simple of construction and operation.

15 Another object of my invention is to provide a device of the above named character which provides a positive lock for the closure when it is desired to secure the same in open position, yet which may be quickly 20 unlocked by releasing the tension on the bolt.

Other objects and advantages of my invention will become apparent from the following description, reference being made to 25 the accompanying drawing forming a part of this application and in which like numerals are employed to designate like parts throughout the same.

In the drawings—

30 Fig. 1 is an elevation showing my device applied to a garage door, preferably on the center panel of the door or about midway of the door length,

Fig. 2 is a plan view of the locking device 35 body,

Fig. 3 is a front view of the same,

Fig. 4 is a front view of the locking bolt,

Fig. 5 is a plan view of the tension means,

Fig. 6 is a side view of the same,

40 Fig. 7 is a perspective view of the bracket, and

Fig. 8 is an enlarged detail of one end of the locking device.

In the drawings, 5 designates a door frame to which I have shown a bearing bracket 6 attached by means of screws 7.

45 The bracket preferably consists of a single piece of metal 6 which may be stamped out of a sheet and which is punched or drilled out at 8 and 9 to form bearing openings. The bracket is bent to the shape shown in Fig. 7, so that the openings 8 and 9 are in vertical alignment. Screw holes 10 are provided for the supporting screws 7.

The fastener or locking device consists of 55 a main body portion and a tensioned bolt adapted to be supported from the bracket and to engage a slot in the fastener body as will be more fully described.

The body portion 11 is preferably formed 60 as shown in Figs. 1, 2 and 3, and consists of a substantially vertical wall 12 which is provided with screw holes 13 for securing the device to the closure. An apertured 65 spring 14 is placed over one of the openings 13 so that the screw 15 will pass through the openings in the spring and vertical wall and into the closure body.

The body portion 11 is preferably formed 70 of a single piece of metal stamped and bent to the form shown in the drawing, but it is to be understood that I may manufacture the body portion in various shapes and sizes according to the use to which they are to be applied.

75 A horizontal wall 16 is formed on the body portion integrally therewith although if desired the wall 16 may be formed as a separate part of the body and be secured thereto in any convenient manner as by welding, or the like. The wall 16 is provided with a slot or guiding 17 running longitudinally of the wall and extending nearly to the ends thereof, for the reception of a bolt element as will be described presently.

80 Each end of the slot communicates with an opening 18 in the wall to form a seat for the bolt. It will be noted that the openings 18 are defined by walls slightly more than semi-circular in shape. That is, if an imaginary line 19, Fig. 8, were drawn at right angles downwardly from the edge of the wall at 20, it would intersect the wall of the opening both at 20 and 21, forming the segment 23 on the chord 19.

85 It will be seen then that each of the openings 18 forms a seat for one end of the bolt 24 which slides in the slot 17, the walls of the openings or sockets describing arcs of more than 180°. The segment indicated at 23 provides a socket where by the bolt end may be retained within the socket against accidental displacement which might otherwise be caused by sudden applications of forces to the closure.

100 105 The bolt consists of a main body 25 which has its ends 24 and 26 bent downwardly, the end 26 being adapted to seat within either of the openings 18 according to whether the

device is used on a left or right moving closure. The other end 24 of the bolt is adapted to pass through the openings 8 and 9 in the bracket where it is hingedly supported, 5 the openings being just large enough to take the bolt end and to permit free movement of the same therein.

Referring again to the spring 14, it will be noted that it consists preferably of a substantially flat strip of spring steel, which is apertured near one end while the main body portion is bent outwardly as at 27. Although, if desired the spring may take various shapes and may consist of any resilient material.

The device is completely assembled to the closure, as, for instance a garage door, as shown in the drawings. As the door is opened, the end 26 of the bolt slides along 20 the slot from a point near the midway point thereof when it comes into contact with the spring 14. As the bolt end nears the seat 18, the maximum tension of the spring will be exerted and when the door has reached the 25 end of its swing, the bolt end 26 will be forced into the seat 18 by the spring and normally held there under considerable tension. It will be noted that the door is held rigidly in this open position and may only 30 be closed by releasing the tension and unseating the bolt end from its seat 18. The door may therefore be left in open position without danger of being blown shut by the wind.

After the doors have been set to the desired open position and it is desired to swing the doors to an extended open position, this may be accomplished by merely removing the bolt ends 24 and 26 from the bracket 6 40 and locking device 11, respectively, and then swinging the door to its full open position.

When it is desired to close the door, the operator may exert pressure against the bolt end 26 and the tension of spring 14 until the 45 end 26 is unseated. Then the door may be closed, and the several parts are restored to their original positions.

While the bolt is thus being pressed toward the door against the spring tension by 50 one hand of the operator, the door is started on its closing swing. During the swing the bolt end 26 travels within the slot 17 toward the other end of the body 11 and as the swing progresses, the bolt is gradually 55 relieved of the spring tension due to the bent end of the spring moving out of contact with the bolt. It will be seen, when the bolt end 26 is seated within one of the openings 18 under tension of the spring 14, that 60 the door is securely held in open position, since the bolt end cannot become unseated from the opening until pressure is applied to it against the tension of the spring. It will also be seen that although the spring 65 14 will prevent displacement of the bolt end

from its seat, such displacement is further prevented due to the peculiar shape of the seat and its remote position with respect to the closure. By arranging the slots or seats 18 so that they extend away from the closure wall I have provided for sufficient leverage whereby the bolt end cannot be displaced from its seat, when seated, even though the spring 14 is out of the path of the mouth of the seat except by applying 70 manual pressure against the bolt end toward the closure. In this connection it is to be noted that I provide the openings 18 of such shape as to help maintain the bolt end within its seat even though the tension 80 of the spring may be materially reduced. This is accomplished by providing an opening substantially circular in shape but slightly more than semi-circular in dimensions so that when the bolt end is seated 85 therein it will be securely held under tension of the spring. I find in practice when the bolt is seated in one of the openings and the door is open, that it is impossible to close the door without first exerting an 90 inward pressure against the bolt end 26 and the spring 14, to unseat the bolt. After the bolt is unseated, the door is easily closed and the bolt end slides within the slot in the member 11 close to the other end thereof. It is to be noted that the top of the member 11 presents a smooth plane surface 95 and offers no obstruction to the passing of the bolt when the door is opened or closed.

An important feature of my invention resides in the reversibility of the device. When it is desired to install the device upon a left hand side of a door or other closure, as shown in Fig. 1, the installation is made as shown, with the bracket on the left hand 105 side of the door frame and the spring extending toward the left.

When it is desired to install the device upon the right hand side of a door frame, it is only necessary to mount the bracket on 110 the right hand side of the frame and to turn the spring 14 so that its bent up end points towards the right as shown in dotted lines in Fig. 1. The bolt is assembled in the bracket 6 and slot 17 and its end 26 seats in 115 the opening 18 in the right hand end of the member 11 when the door is opened. Thus it will be seen that the device may be applied to either the right or left hand side 120 of a closure frame. It is to be understood also that the device may be applied to closures which swing or rotate on an axis other than that in a vertical plane.

It will be seen that due to the extreme 125 simplicity of the device, ease of operation and small number of working parts, I have provided a device which is very inexpensive to manufacture.

It is to be noted that I have provided 130 means for securing a closure in an open

position exceeding 90°, if desired, so that the closure may be secured out of the path of the opening in the closure frame. This may be accomplished by predetermined positioning of the bracket or body 11, upon the closure, as for instance, the shorter the distance between the hinged end of the closure and the nearest end of the bracket 11, the greater will be the arc thru which the closure may swing and be locked in open position.

Various changes in the size, shape and construction and operation of the invention may be made without departing from the spirit of the invention or the scope of the subjoined claims.

I claim:

1. A closure fastener comprising a rigid member having a slot engaging portion at one end, a bracket fixed to a support and pivotally connected to the said rigid member, and a second bracket carried by another

supporting member and having an elongated slot for slidably receiving the said slot engaging portion of the said rigid member, 25 the said slot having at one end a portion extended laterally away from the member supporting the said second bracket and adapted to retain the rigid member therein.

2. A closure fastener comprising a rigid member having a slot engaging portion at one end, a bracket fixed to a support and pivotally connected to the said rigid member, and a second bracket carried by a closure and having an elongated slot for slidably receiving the said slot engaging portion of the said member, the said slot having at one end a portion extended laterally away from the closure and adapted to retain the rigid member therein. 40

In testimony whereof I hereunto affix my signature this 15th day of April, 1925.

JOHN A. RICE.
